WALTER FERRIS, OF MILWAUKEE, WISCONSIN, ASSIGNOR TO THE OILGEAR COMPANY, OF MILWAUKEE, WISCONSIN, A CORPORATION OF WISCONSIN.

PUMP OR MOTOR.

Application filed April 28, 1924. Serial No. 709,527.

This invention relates to pumps or fluid motors of the radial, multiple cylinder type.

One object of the present invention is the provision of a compact pump or motor of increased capacity. This is accomplished by a novel compact arrangement of parts permitting the use of a maximum number of cylinders, each of maximum capacity, within a limited operating space.

Another object is the provision in a pump or motor of the type mentioned of a novel arrangement of parts permitting a pintle construction of maximum strength, to thereby permit the use of high operating pressures without danger of pintle distortion.

Another object is the provision of an improved piston and cylinder assembly for pumps and motors of this type.

These and other objects and advantages will appear from the following description of an illustrative embodiment of the present invention.

In the accompanying drawings:

Figure 1 is a sectional view of a variable displacement pump constructed in accordance with the present invention.

Figure 2 is a sectional view taken substantially upon the line 2—2 of Figure 1.

The pump selected for illustration is shown enclosed in a casing 10. It comprises a cylinder barrel 11, rotatably mounted upon a fixed pintle 12, and an impelling cage 13 rotatably mounted within a cradle 14. The pintle shown is supported at both ends in bosses 15 formed integral with the removable side plates 16 of the casing 10. In this instance, the pintle is of hollow form having an inclined partition 17 separating the opposite ends thereof into fluid receiving and discharge passages, respectively. Three sets of ports in spaced parallel planes extend through the wall of the pintle. Each set comprises a pair of upper ports 18 disposed above the partition 17 and communicating with the left hollow end (Fig. 2) of the pintle and a pair of lower ports 19 disposed below the partition 17 and communicating with the right hollow end of the pintle. The opposite ends of the pintle communicate with conduits 20 and 21, respectively, connected with the bosses 15.

In the pump shown, the cylinder barrel 11 is provided with nine radially disposed cylinder bores 22, equally spaced about the axis of the pintle. These bores are arranged in

groups of three, those of each group being equally spaced about the pintle and lying in the plane of one of the sets of pintle ports above referred to. At the base of each cylinder bore the cylinder barrel is gashed to form a fluid passage 23 open to the pintle and adapted to effect communication between the cylinder bore and the upper and lower pairs of ports 18 and 19, respectively, during rotation of the cylinder barrel. The distance between the two ports 18 and between the two ports 19 is somewhat less than the distance between either of the ports 18 and the nearest port 19. The length of the passage 23 is greater than the distance between ports 18 or 70 between ports 19 so that it is capable of bridging across the ports of either pair, but its length is a trifle less than the distance between either of the ports 18 and the nearest port 19 so that it is never in communication 75 with ports 18 and 19 at the same time. The arrangement is such that as each cylinder bore 22 is carried by the rotating cylinder barrel through the upper portion of its circular course, the bore communicates through its passage 23 with one or both of the ports 18, and during the lower portion of its course it communicates through the passage 23 with one or both of the ports 19. In each brief transitional stage of each cylinder bore between the upper and lower portions of its course, the communicating passage 23 is out of communication with the ports.

By the provision of passages of this character in the cylinder barrel capable of functioning in the manner above described, I avoid the use of gashes in the upper and lower surfaces of the pintle which were heretofore believed necessary in a pump or motor of this type. By doing away with gashes in the 90 pintle, the pintle is better able to sustain exceedingly heavy loads without danger of distortion. The use of only three cylinder bores within one plane of rotation renders it possible to gash the cylinder barrel in this manner without danger of short circuiting successive cylinder bores.

In the pump shown the impelling cage 13 is in the form of a cylindrical casting having end hub portions 24 and 25 journaled upon roller 105 bearings 26 and 27 supported upon rings 28 and 29, constituting integral parts of the cradle 14. Nine tangential guideways 30 are formed in the cylindrical cage 13. These are disposed in groups of three in spaced parallel 110

planes corresponding to the planes of the cylinder bores. Each guideway is disposed opposite and extends normal to the axis of a cylinder bore 22. A crosshead 31 is mounted 5 for lengthwise reciprocation in each guideway and is connected with a piston 32 closely fitted for reciprocation in the corresponding cylinder bore 22. An elongated opening 33 is formed through the base of each guideway 10 to accommodate the piston 32 and to permit the piston to reciprocate with the crosshead. In the pump shown each guideway 30 is somewhat narrower than the corresponding piston 32. The side walls of each guideway are 15 therefore preferably grooved, as at 34, intermediate their ends, to provide sufficient clearance to permit the insertion or removal of the piston into or from its cylinder bore radially through the cylindrical wall of the impelling 20 cage 13. The side walls of each guideway are also longitudinally grooved, as at 35, to receive and sustain a reaction plate 36 in position substantially parallel with the corresponding crosshead 31. Each plate 36 is removably fixed in this position by a lock plate 25 37 secured thereto by a screw 38. Lock plate 37 extends across the plate 36 with its ends projecting into the grooves 34.

A set of load transmitting rollers 39 is 30 interposed between each crosshead 31 and corresponding reaction plate 36. These rollers serve to transmit the pressure between the crosshead and reaction plate and react under the pressure to maintain these elements in 35 parallelism to thereby cause the cylinder barrel and impelling cage to rotate in unison. These rollers also permit free reciprocation of each crosshead along the corresponding guideway 30 parallel to the corresponding reaction plate 36 during rotation of the cage and cylinder barrel. Rollers 39 are preferably connected by a link 40 which serves to maintain them in proper spaced relation. The link 40 is preferably provided with a 45 recess 41 into which the end of screw 38 projects to limit the travel of the rollers.

The cradle 14, carrying the bearing rings 28 and 29, is rockably supported upon a power transmission shaft 42 journaled in fixed bearings 43 and 44 in the casing 10. This shaft is 50 rotatably fitted in bearings 45 and 46 formed integral with the cradle. A gear 47 fixed to shaft 42 meshes with a gear ring 48 formed upon the hub 25 of the impelling cage 13.

By rocking the cradle 14 about the axis of the shaft 42 the axis of rotation of the impelling cage 13 may be adjusted horizontally 55 from a position substantially coincident with the axis of rotation of the cylinder barrel 11 to a position at either side thereof. When these two axes are coincident, rotation imparted to the impelling cage and cylinder barrel results in a circular travel of the pistons and cylinders about the pintle without relative reciprocation between the pistons and

cylinders. Under this condition no flow of fluid occurs in the pintle. When the cradle 14 is rocked so as to shift the axis of rotation of the impelling cage out of this neutral position, rotation of the cage and cylinder barrel 70 causes a relative reciprocation between the pistons and cylinders to an extent dependent on the distance between the axes of rotation of the cage and cylinder barrel.

For purposes of illustration, let it be assumed that the parts are in the position indicated in Figure 1 with the axis x of the impelling cage disposed to the left of the axis y of the cylinder barrel and that power is applied through shaft 42 and gears 47 and 48 75 to drive the impelling cage 13 in a clockwise direction. The cylinder barrel 11, through the pressure transmitted through the rollers 39 from the reaction plates 36 to the crossheads 31, rotates in the same direction. During this rotation the pistons 32, in the upper half of their circular travel, move inwardly in the cylinder bores 22, thereby forcing liquid from the cylinder bores through passages 23 and ports 18 into the left end of the hollow pintle 12 (Fig. 2); and during the lower half of their circular travel the pistons move outwardly in their cylinder bores, thus 80 permitting fluid to pass from the right end of the pintle, through ports 19 and passage 23, into the cylinder bores. Under this condition of operation fluid received from conduit 21 is discharged through conduit 20. By rocking the cradle so as to shift the axis x 85 to the other side of the axis y , the pistons, during the upper half of their travel, move outwardly in their cylinder bores, and during the lower half of their travel move inwardly to thereby change the direction of flow of the fluid in the pintle. In all positions of the cradle 14 the gears 47 and 48 remain in mesh 90 so that the impelling cage is always operatively connected with the shaft 42.

Any appropriate means, such as a screw 49 95 swiveled, as at 50 and 51, in the casing 10, and threaded through a block 52 carried by the cradle 14, may be employed to swing and control the cradle 14, to thereby regulate and control pump displacement. The screw 49 is controlled by a hand wheel 53 fixed to the end 100 thereof. The block 52 is fitted between a pair of upstanding ears 54 formed upon the cradle 14, and is provided with trunnions 55 engaged within vertical slots 56 formed in the ears 54.

It will be noted that in the pump shown, the driving pressure between the teeth of the gears 47 and 48 results in a reaction upon the cradle 14 tending to rock the cradle about the shaft 42 against the restraining action of the regulating screw 49. Thus, assuming that the shaft 42 and gear 47 are rotating in the direction indicated by the arrow in Figure 1, so as to rotate the pump in a clockwise direction, the driving pressure thus applied to the 105 110 115 120 125 130

gear 48 is transmitted through the cage 13 and bearings 26 and 27 to the cradle 14 tending to rock the cradle toward the left (Fig. 1). Provision is preferably made to counteract this effect and, in the pump shown, mechanism for this purpose comprises a pair of plungers 63 and 64 reciprocable in bores 65 and 66 formed in a block 67 in the casing 10. Bore 65 communicates through a pipe 68 with one end of the pintle while bore 66 communicates through a pipe 69 with the other end of the pintle. Both plungers 63 and 64 bear against a face 70 formed upon the cradle 14. The arrangement is such that the high pressure fluid in one or the other ends of the pintle is transmitted through one of the pipes 68 or 69 to the corresponding bore 65 or 66, to thereby force one of the plungers 63 or 64 against the face 70, in such direction as to counteract the effect of the gears 47 and 48 thereon. Since the driving pressure between the teeth of gears 47 and 48 is substantially proportional to the pressure of fluid delivered by the pump the plungers 63 and 64 may be so proportioned that they thus will substantially counterbalance the effect of the gears.

From a strictly theoretical point of view, it would appear that for perfect operation it would be necessary to rigidly connect each crosshead 31 with its corresponding piston 32, in order to transmit sufficient torque from the impelling cage 13 to cause rotation of the cylinder barrel 11. In actual practice, however, it has been found that it is at least highly desirable to permit a very limited rocking action between each crosshead and piston in order to avoid binding action between the pistons and cooperating cylinder bores due to inaccuracies in the machine. Such inaccuracies may arise from inaccurate machining or positioning of the parts or from distortion of the parts under load.

This limited rocking action may be provided in various ways, but in the pump shown this is accomplished by forming each crosshead 31 with an integral stem 57 adapted to project loosely into and bear upon the bottom 58 of the hollow piston 32. A bore 57' extending through the crosshead and into the stem 57 is formed to receive a compressing spring 59. Spring 59 is maintained under compression by a headed rivet 60 inserted loosely into the bore 57' and projected through an appropriate aperture 61 in the lower end of the stem into the bottom of the piston. It is fixed in the bottom of the piston, as at 62, by riveting or otherwise. The compression of spring 59 is sufficient to maintain a bearing contact between the stem and the bottom of the piston during a suction stroke thereof. Sufficient clearance is provided between the stem 57 and internal walls of the piston and between the head of the rivet 60 and the walls of the bore 57' to permit the

desired limited rocking action between the crosshead and piston in all directions.

The mechanism above described will operate as a motor as well as a pump. Fluid delivered under pressure through one of the conduits 20 or 21 and applied through the pintle and ports 18 or 19 to the pistons 32 will cause rotation of the impelling cage 13 in one direction or another dependent upon the relative positions of the axes of rotation x and y . Rotation of the cage 13 will, of course, be transmitted through the gears 47 and 48 to the shaft 42. The speed and direction of rotation of the shaft 42 may thus be varied and controlled by turning the screw 49 to thereby adjust the cradle 14 about the shaft 42.

Various changes may be made in the embodiment of the invention hereinabove described, without departing from or sacrificing any of the advantages of the invention as defined in the appended claims.

I claim:

1. In a pump or motor the combination of a pintle, a cylinder barrel rotatable thereon and having nine cylinders radially disposed and equally spaced about the axis of rotation thereof, said cylinders being arranged in groups of three, each group lying in a plane offset along said axis from the plane of an adjacent group, nine pistons reciprocable in said cylinder bores, respectively, and a rotary member cooperating with said pistons and cylinders to effect relative reciprocation therebetween.

2. In a pump or motor the combination of a pintle, a cylinder barrel rotatable thereon and having an odd number of cylinders radially disposed and equally spaced about the axis of rotation thereof, said cylinders being arranged in groups disposed in planes offset along said axis, a piston reciprocable in each cylinder, and an impelling member cooperating with said pistons and cylinders to effect relative reciprocation therebetween.

3. In a pump or motor the combination of a pintle, a member rotatable thereon, an impelling rotatable member surrounding said first named member and an odd number of piston and cylinder assemblies radially disposed between said members, said assemblies being arranged in groups, each group lying in a plane laterally disposed with respect to the plane of an adjacent group.

4. In a pump or motor the combination of an odd number of piston and cylinder assemblies substantially radially disposed and equally spaced about an axis, said assemblies being arranged in groups offset in the direction of said axis, and means for effecting relative reciprocation between the pistons and cylinders of the respective assemblies.

5. In a pump or motor the combination of a pintle having a pair of spaced intake ports

- and a pair of spaced discharge ports, a member rotatable on said pintle and having a channel open to said pintle and adapted to bridge the space between the ports of either 5 pair, a piston and cylinder assembly in constant communication with said channel, and a member associated with said assembly to effect relative reciprocation between the piston and cylinder thereof.
- 10 6. In a pump or motor the combination of a pintle having intake and discharge ports, a member rotatable thereon and having a plurality of channels extending circumferentially of and open to said pintle, each channel adapted to communicate with said intake and discharge ports, alternately, during rotation of said member, a plurality of piston and cylinder assemblies each communicating with one of said channels, and means cooperating 15 with said assemblies to effect relative reciprocation between the pistons and cylinders thereof.
7. In a pump or motor the combination of a pintle having intake and exhaust ports, a cylinder barrel rotatable thereon having a plurality of radially disposed cylinder bores, a plurality of channels in said cylinder barrel, each communicating with one of said cylinder bores and extending circumferentially of said pintle in the plane of said ports, a piston reciprocating in each cylinder bore, and a member cooperating with said pistons to effect reciprocation thereof.
8. In a pump or motor the combination of a pintle, a support for each end thereof, a member rotatable on said pintle intermediate the ends thereof, a rotary impelling member, a series of radially disposed piston and cylinder assemblies between said members, and means for effecting a relative adjustment between said members to regulate the displacement of said pump or motor.
9. In a pump or motor the combination of a pintle, a member rotatable thereon, a rotary impelling member adjustable relative to said first named member, a series of piston and cylinder assemblies between said members, means for adjusting said last named member, a shaft, fixed bearings for said shaft, and driving connections between said shaft and impelling member permitting adjustment thereof.
10. In a pump or motor the combination of a pintle, a member rotatable thereon, a second rotatable member, a series of piston and cylinder assemblies between said members, a rockable support for said last named member, means for adjusting said support, a shaft, fixed bearings therefor, and gear connections between said shaft and last named member.
11. In a pump or motor the combination of a series of radially disposed piston and cylinder assemblies, a crosshead associated with each assembly, an impelling member having a series of reaction faces, each opposite one of said crossheads, and connections between each crosshead and associated assembly permitting a limited rocking action therebetween in all directions.
12. In a pump or motor the combination of a series of radially disposed piston and cylinder assemblies, a crosshead associated with each assembly, an impelling member having a series of reaction faces, each opposite one of said crossheads, and connections between each crosshead and associated assembly permitting a limited rocking action therebetween in the plane of said series of assemblies.
13. In a pump or motor the combination of a series of radially disposed piston and cylinder assemblies, an impelling member having a series of reaction faces, each disposed substantially normal to and opposite one of said assemblies, a crosshead reciprocable along each face and associated with the adjacent assembly, and resilient means maintaining each crosshead in proper working relation with the associated assembly.
14. A pump or motor having a series of cylinders, a hollow piston reciprocable in each cylinder, a crosshead having a stem projecting loosely into said piston, and a spring operable to maintain said piston and crosshead in assembled relation.
15. In a pump or motor the combination of two rotary members, fluid impelling means between said members, one of said members being movable to vary the capacity of said means, power transmission mechanism reacting upon said movable member tending to shift said member, and fluid pressure responsive means automatically operable to counteract the reaction of said mechanism.
16. In a pump or motor the combination of a rotary cylinder barrel, a rotary impelling member movable relative thereto, a series of piston and cylinder assemblies between and cooperating with said members, a gear carried by said impelling member, a second gear in driving relation with said first named gear, and fluid pressure responsive means automatically operable to counteract the thrust of said gears upon said impelling member.
17. In a pump or motor the combination of a rotary cylinder barrel, a rotary impelling member, a series of piston and cylinder assemblies radially disposed between said members, a movable support for said impelling member, and a gear carried by said impelling member and movable therewith, a second gear rotatable about a fixed axis and meshing with said movable gear, the reaction between said gears tending to shift said support, and fluid pressure responsive means automatically operable to counteract the effect of said gears upon said movable support.

In witness whereof, I hereunto subscribe my name this 22nd day of April, 1924.

WALTER FERRIS.
